UNITED STATES PATENT OFFICE

RUBEN B. LUSTIG, OF KANSAS CITY, MISSOURI

DESIGN FOR A DISPLAY STAND

Application filed March 9, 1931. Serial No. 39,004. Term of patent 14 years.

To all whom it may concern:

Be it known that I, RUBEN B. LUSTIG, a citizen of the United States, and resident of Kansas City, in the county of Jackson and State of Missouri, have invented a new, original, and ornamental Design for Display Stand, of which the following is a specification, reference being had to the accompanying drawings, forming part thereof, in which,

Fig. 1 is a perspective view of the display stand showing my new design. Fig. 2 is an end elevation of the same.

I claim:

The ornamental design for a display stand, as shown.

Dated, March, 1931.

RUBEN B. LUSTIG.
